209,758

COMBINED TABLE AND BENCH UNIT

Robert O. Blink, Milwaukee, Frederick H. Holz, Wauwatosa, and William C. Lutzke, Milwaukee, Wis., assignors to Mitchell Manufacturing Company, Milwaukee, Wis., a corporation of Wisconsin

Filed June 6, 1966, Ser. No. 2,566

Term of patent 14 years

(Cl. D33—14)

Fig. 1

Fig. 2

*FIG. 3*FIG. 1 is a perspective view of a combined table and bench unit showing our new design;

FIG. 2 is a top plan view thereof; and

FIG. 3 is another perspective view thereof more from the side and showing the side and remote end characteristics of the combined table and bench unit.

The leg unit and brace elements shown at the front end of the table in FIG. 1 is duplicated at the middle and remote ends of the unit.

We claim:

The ornamental design for a combined table and bench unit, substantially as shown and described.

UNITED STATES PATENT OFFICE

Certificate

Patent No. D. 209,758

Patented January 2, 1968

Robert O. Blink, Frederick H. Holz and William C. Lutzke

Application having been made by Robert O. Blink, Frederick H. Holz, and William C. Lutzke, the inventors named in the patent above identified, and Mitchell Manufacturing Company, Milwaukee, Wis., a corporation of Wisconsin, the assignee, for the issuance of a certificate under the provisions of Title 35, Section 256, of the United States Code, adding the name of Robert W. Schier as a joint inventor, and a showing and proof of facts satisfying the requirements of the said section having been submitted, it is this 1st day of September 1970, certified that the name of the said Robert W. Schier is hereby added to the said patent as a joint inventor with the said Robert O. Blink, Frederick H. Holz, and William C. Lutzke.
